SLIDING JAW SUPPORTING CLASP

Hugh P. Botts, New York, N. Y., assignor of one-half to Lawrence G. Botts, New York, N. Y.

Application October 19, 1944, Serial No. 559,426

5 Claims. (Cl. 24—263)

1

This invention relates to clasp devices adapted for use in connection with garters or other supporting straps of any kind or class to engage or grasp an article for supporting the latter. More particularly, the invention relates to devices of this class comprising an elongated tapered body part and a tapered sleeve slidably engaging the body part and forming a wedge element coacting with the body part to engage and retain an article within and between coacting bevelled surfaces of the body part and sleeve. The invention also further deals with devices of this kind wherein the body part includes at one end thereof an apertured head for engagement of a strap or band therewith. The novel features of the invention will be best understood from the following description when taken together with the accompanying drawing, in which certain embodiments of the invention are disclosed, and in which the separate parts are designated by suitable reference characters in each of the views; and in which:

Fig. 1 is a face view of a clasp device shown in a detached position.

Fig. 2 is a view similar to Fig. 1, showing the gripper sleeve of the device in a raised position.

Fig. 3 is a side edge view of the device as seen in Fig. 1.

Fig. 4 is a bottom plan view of the device as seen in Fig. 1.

Fig. 5 is a perspective view of the device shown in Figs. 1 to 4 inclusive as applied to part of the leg encircling band of a garter preparatory for attachment of a sock or stocking therewith.

Fig. 6 is a view similar to Fig. 5, showing a complete garter and illustrating the clasp device engaging the upper edge portion of a stocking; and

Fig. 7 is a perspective view of another form of clasp device which I employ in illustrating another use thereof.

In Figs. 1 to 6 inclusive, I have shown at 10 an elongated body part of a clasp device, the central portion of which is defined by tapered walls 11 converging in the direction of the upper enlarged head end 12 of the body portion. The head end 12 has a pair of spaced elongated apertures 13 which slightly converge toward each other in the direction of the upper end of said head. The lower end 14 of the body portion 10 is also enlarged and defined by outwardly bulged rounded side edges 15.

Arranged upon the body portion 10 is a narrow sleeve 16 in the form of a split ring or band of a width less than half the length of said central

2

portion, the ends of which terminate in rounded surfaces 17, which as will latter appear, facilitates attachment of the clasp to suitable supports or garments. The side walls 18 of the sleeve 16 converge upwardly and substantially parallel the converging side edges 11 of the body portion 10. The curved ends 17 are spaced apart, as seen at 19, to provide clearance for the support or garment to which the clasp is attached, as will clearly appear from a consideration of Fig. 6 of the drawing.

Considering Fig. 4 of the drawing, it will appear that the sleeve 16, which may be referred to as the clamp or coupling sleeve, has its walls sufficiently spaced from the walls of the body 10 to provide clearance for free insertion of the support or garment to be engaged by the clasp.

As seen in Figs. 5 and 6 of the drawing, a strap or band 20, which may constitute part of a leg encircling garter is threaded through the apertures 13 in the head 12, and the ends of the band 20 have suitable and more or less conventional couplings 21 and 22 for securing the ends together around the body of a wearer.

25 In the use of the clasp device, it will be apparent that the coupling sleeve 16 is raised upon the body 10 in the manner illustrated, for example, in Figs. 2 and 5 of the drawing, and then a support to be engaged by the clasp, such for 30 example as the upper edge portion 23 of a sock or stocking, is wrapped outwardly around the body portion 10 including the bevelled or converging side edges 11 thereof, as well as around the lower end 14. The portions 24 and 25 of the sock or stocking are then brought together in close proximity centrally of the front of the body 10 and in alignment with the opening 19 in the sleeve 16, after which the sleeve is moved downwardly over the sock or stocking 23 with parts 24 and 35 25 passing through the opening 19 until the sock or stocking is firmly engaged between the tapered side walls 18 of the sleeve and the bevelled edges 11 of the body 10, the result of which operation is indicated in Fig. 6 of the drawing. To release 40 the sock or stocking, the sleeve 16 is simply drawn upwardly.

In Fig. 7 of the drawing is shown a slight modification wherein the body portion 26 of the clasp device has tapered side edges 27, similar to the edges 11, and a sleeve 28 similar to the sleeve 16 is employed. The lower end 29 of the body 26 is substantially the same as the end 14, whereas as the head end 30 has a single transverse aperture 31 at the upper end portion thereof to receive the loop 32 of a supporting strap 33 se-

cured to a suitable garment, part of which is indicated at 34 in this figure.

The garment or supporting member 34 may comprise a girdle, corset or similar garment, or part of a garter belt or similar supporting medium for use in holding women's and misses' stockings in position through the medium of the clasp device suspended from the supports in question through the strap 33. It will also be apparent that the clasp device may be suitably supported in connection with other types and kinds of garments where it is desirable to support or hold articles of any type or kind in position, and in this respect need not necessarily be applied to articles of apparel and may be used as a coupling or clasp for general purposes and uses of devices of this kind.

The device shown in Fig. 7 will operate substantially in the same manner as the devices shown in Figs. 1 to 6 inclusive. In both devices, it will appear that they are of economic construction and can be composed of sheet material, and in referring to sheet material, both metal and plastic materials are to be considered. In some instances, the materials may be cast or molded to further simplify manufacturing costs, and here reference is particularly made to the use of plastic materials, particularly such materials as capable of being die cast or molded. In using plastics, the material may be transparent or substantially so, thus presenting a sanitary appearance. On the other hand, the same may be composed of various colored materials in harmony with uses to which they are applied, or consistent with the strap or other members used in conjunction therewith. It will also be understood that the body part of the clasp may be of one color and the coupling or clamping sleeve of another color.

Devices of the kind defined may be constructed at nominal costs and by reason of the structure employed, become substantially foolproof in use in obtaining a positive engagement with garments or other members to which the clasp is attached. Furthermore, this engagement is accomplished without injury thereto.

In uses on stockings, the clasp will minimize the strain upon the stocking, which strain tends to develop runs therein. This clasp minimizes strains by reason of a wider spread of engagement of the device with the upper edge portion of the stocking.

It will appear that the body portion of the clasp device may be defined as having a reduced central portion or shank with means in the form of enlarged heads or ends for retaining the clamping or gripper sleeve against displacement from the body. It will also appear that sliding movement of the sleeve on the shank of the body into the gripping position will be governed largely by the thickness of the material interposed between the shank and sleeve. Still further, it will appear that in providing spaced apertures in the upper head end of the body, these apertures will provide adjustment of the body longitudinally of a supporting strap for positioning the body on the strap.

Having fully described my invention, what I claim as new and desire to secure by Letters Patent is:

1. A clasp device for garters and similar supporting straps, said device comprising an elongated member, said member being defined by enlarged upper and lower ends directly joined by a long central portion having side edges con-

verging to said upper end, a narrow split clamping sleeve slidably engaging said member intermediate said ends and retained against displacement from said member by said ends and said sleeve having tapered side walls arranged adjacent and paralleling the converging side edges of said central portion, whereby a sheet member folded around said member may be firmly clamped on said member by wedging engagement of the sheet member between the tapered walls of said sleeve and the converging side edges of said member.

2. A clasp device for garters and similar supporting straps, said device comprising an elongated member, said member being defined by enlarged upper and lower ends directly joined by a long central portion having side edges converging to said upper end, a narrow split clamping sleeve slidably engaging said member intermediate said ends and retained against displacement from said member by said ends, said sleeve having tapered side walls arranged adjacent and paralleling the converging side edges of said central portion, whereby a sheet member folded around said member may be firmly clamped on said member by wedging engagement of the sheet member between the tapered walls of said sleeve and the converging side edges of said member, and the enlarged upper end of said member having means for coupling a strap therewith.

3. A clasp device for garters and similar supporting straps, said device comprising an elongated member, said member being defined by enlarged upper and lower ends directly joined by a long central portion having side edges converging to said upper end, a narrow split clamping sleeve slidably engaging said member intermediate said ends and retained against displacement from said member by said ends, said sleeve having tapered side walls arranged adjacent and paralleling the converging side edges of said central portion, whereby a sheet member folded around said member may be firmly clamped on said member by wedging engagement of the sheet member between the tapered walls of said sleeve and the converging side edges of said member, the enlarged upper end of said member having means for coupling a strap therewith, and said last named means comprising spaced elongated apertures extending longitudinally of said member.

4. A clasp device for garters and similar supporting straps, said device comprising an elongated member, said member being defined by enlarged upper and lower ends directly joined by a long central portion having side edges converging to said upper end, a narrow split clamping sleeve slidably engaging said member intermediate said ends and retained against displacement from said member by said ends, said sleeve having tapered side walls arranged adjacent and paralleling the converging side edges of said central portion, whereby a sheet member folded around said member may be firmly clamped on said member by wedging engagement of the sheet member between the tapered walls of said sleeve and the converging side edges of said member, and the enlarged lower end of said member having curved side walls joining the tapered side walls of the central portion.

5. A clasp device for garters and similar supporting straps, said device comprising an elongated member, said member being defined by enlarged upper and lower ends directly joined

by a long central portion having side edges converging to said upper end, a narrow split clamping sleeve slidably engaging said member intermediate said ends and retained against displacement from said member by said ends, said sleeve having tapered side walls arranged adjacent and paralleling the converging side edges of said central portion, whereby a sheet member folded around said member may be firmly clamped on said member by wedging engagement of the sheet member between the tapered walls of said sleeve and the converging side edges of said member, the enlarged lower end of said member having curved side walls joining the tapered side walls of the central portion, and the ends of the 15 sleeve at the split therein being rounded.
